UNITED STATES PATENT OFFICE.

LEO J. GRUBMAN, OF NEW YORK, N. Y.

SOUND-PRODUCING DEVICE.

Application filed August 7, 1923. Serial No. 656,167.

To all whom it may concern:

Be it known that I, LEO J. GRUBMAN, a citizen of the United States, and a resident of the city, county, and State of New York, 5 have invented certain new and useful Improvements in Sound-Producing Devices, of which the following is a specification.

This invention relates to sound producing devices for toys and particularly to a device 10 of that type which is incorporated within the body of a doll for the purpose of simulating an infant cry such as the exclamation "Ma-Ma."

It is the primary object and purpose of 15 my present improvements to provide a sound producing device of the above character in which the several parts controlling the emission of the sound in producing the articulation of the word syllables are of simple 20 and substantial construction so that, although the doll or toy may be subjected to abusive handling, the parts of the device are not likely to be damaged to such extent as to render the device inoperative.

25 One of the prominent features of this invention resides in the provision of a tubular movably supported air expelling member whereby air is expelled under pressure through a sound producing reed, and a 30 sound receiving chamber having a wall adapted to be telescopically received within the tubular expelling member, the wall of said expelling member being provided with sound emission control openings therein 35 through which the sound is emitted into said sound receiving chamber in the movement of the expelling member in one direction.

It is another object of my invention to 40 materially simplify the form and construction of the air expelling member and movable sound control means and to so arrange and support the same for operative movement and the proper interrupted emission of the sounds that the perfect articulation 45 of the word syllables is assured under all conditions of use.

With the above and other objects in view 50 the invention consists in the improved sound controlling device and in the form, construction and relative arrangement of its several parts as will be hereinafter more fully described, illustrated in the accompanying drawing and subsequently incorporated in the subjoined claims.

55 In the drawing wherein I have illustrated one simple and practical embodiment of the

invention and in which similar reference characters designate corresponding parts throughout the several views;

Figure 1 is a longitudinal sectional view 60 illustrating a preferred embodiment of my present improvements showing the air expelling member at the end of its operating movement;

Figure 2 is a similar view showing the device in inverted position;

Figure 3 is a horizontal sectional view taken on the line 3—3 of Figure 1;

Figure 4 is an end elevation;

Figures 5 and 6 are sectional views similar to Figs. 1 and 2 illustrating an alternative embodiment of the device;

Figure 7 is an end elevation of the latter construction; and

Figure 8 is a horizontal section taken on 75 the line 8—8 of Figure 5.

My present disclosure relates more particularly to that type of sound producing device in which the air is expelled from a chamber through a sound producing reed by 80 a gravity movable piston or plunger, as distinguished from the bellows type wherein the air expelling member or head is fixed to one end of a collapsible flexible wall or membrane. The several parts which function to produce the desired sounds are enclosed within an outer drum or casing 5, preferably, though not necessarily, formed of heavy cardboard. One end of this casing is closed by means of the sheet metal head 6 90 having a marginal flange frictionally engaging the outer face of the casing wall.

Within the casing 5 and concentrically spaced from the wall thereof a shell 7, also preferably of sheet metal is arranged. This 95 shell at one of its ends is open and the wall thereof is formed with a horizontal annular flange or shoulder 8 connecting the body of the shell with a channelled or U-shaped rim 9 which receives the other end edge of the casing wall, the inner and outer side portions of said rim having tight frictional engagement against the inner and outer faces of the casing wall. The other end of the shell 7 is closed by the wall 10, a sound producing reed 11 of any conventional form being mounted upon the inner face of said wall over the aperture 12 therein. Intermediate of its ends the body wall of the shell 7 is provided with a series of circumferentially spaced sound emission openings 110

Within the shell 7 a heavy metal air expelling member 14 is arranged. This air expelling member is of tubular form, open at one of its ends and closed at its other end 5 by the wall 15 to which a cup leather 16 is securely fixed by means of the plate 17 and rivet 18. The marginal flange of this cup leather has frictional sliding contact with the inner surface of the shell 7. Thus a 10 substantially air tight barrier is produced between one side of the member 14 and the open end of the shell 7. The wall of the tubular member 14 is spaced from the wall of the shell 7 only sufficiently to avoid frictional contact therewith, and said wall adjacent the open end of the tubular air expelling member is provided with circumferentially spaced openings 19 therein.

In the open end of the shell 7 a sleeve 20 is arranged, the wall of said sleeve being disposed in spaced concentric relation with the wall of the shell 7. The inner end of said sleeve is closed by the wall 21, and at its outer end the sleeve wall is formed with 25 a laterally disposed angular flange 22 which has a tight frictional fit within the inner wall of the channeled rim 9 on the end of the shell 7. The closed end 21 of the sleeve 20 is positioned inwardly of the series of 30 openings 13 in the shell wall and the wall of said sleeve is provided with circumferentially spaced openings 23 corresponding in number to the openings 19 in the wall of the tubular air expelling member 14.

35 The air expelling member 14 is sufficiently heavy to move freely by gravity into one end of the shell 7 and as this member moves to the position seen in Figure 2 of the drawings, air is drawn into one end of the shell 40 through the openings 23 and 13 and the reed aperture 12.

When the device is inverted to the position seen in Figure 1, as the air expelling member starts to move downwardly with 45 relation to the sleeve 20, the air beneath said member is expelled past the reed 11, thereby producing sound which is emitted into the space between the shell 7 and the wall of the casing 5. The sound waves first 50 escape in small volume from this space through the openings 13 and between the wall of the shell and the wall of the member 14 and are emitted through coinciding openings 19 and 23 into the sleeve 20 in simulation of the spoken pronunciation of the letter "m." As the member 14 continues its 55 downward movement, when the openings 19 therein register with the openings 13 of the shell wall, the sound waves are emitted in greater volume and simulate the pronunciation 60 of the spoken letter "a." When the openings 19 pass below the openings 13 and the end portion of the wall of the member 14 is positioned over the latter openings, the 65 volume of sound emitted is again reduced to

simulate the pronunciation of the letter "m" for a second time and when the member 14 finally moves to a position entirely below the openings 13, there will be a prolonged sounding of the final vowel letter "a." The 70 interior of the sleeve 20 provides a sound receiving and amplifying chamber of constant definite area as in my Patent No. 1,490,170, issued April 15, 1924, the wall of said sleeve acting as a resonator. The controlled emission of the sounds produced by the expulsion of the air past the reed 11 results in a very realistic simulation of the spoken articulation of the word syllables, 75 which are amplified and rendered very distinctly audible in their passage through the sleeve 20. By merely again inverting the device or the toy within which it is contained, the chamber between the piston or expelling member 14 and the end wall of 80 the shell may be again filled with air for the repeated operation of the device in the manner above explained.

In Figures 5 to 8 inclusive of the drawings I have illustrated another construction 90 which is perhaps simpler and less expensive than the embodiment of the device shown in Figs. 1 and 2. In this modified construction the inner shell 7 above referred to is dispensed with and the sound emission openings 13' are formed in the wall of the casing or housing within which the hollow air expelling member 14' is mounted for reciprocating movement. In this instance, however, a head 25 is fitted into the open end of 95 said member and is provided with marginal means for frictionally engaging and clamping one edge of a packing ring or gasket 26 which has frictional sliding contact with the inner face of the wall of the casing 5'. The space between the outer side of the head 25 and one end of said casing constitutes the air receiving chamber 20', while the space between the inner side of said head and the other closed end of the member 14' constitutes a sound chamber 27. The head 25 is provided with an opening 25' in the wall thereof over the outer side of which the free 100 end of the vibratory sound producing element 11' is disposed. The circumferential wall of the sound chamber 27 is provided with suitably spaced openings 19' therein which are adapted to co-operate with the openings 13' in the wall of the casing 5' and control the articulated emission of the 105 sound through the latter openings in the air expelling movement of the member 14'.

One end of the casing 5' is closed by the sheet metal head 28 having a central air inlet opening 29 therein. This head is positioned inwardly of the end edge of the casing wall and is integrally connected by means of the annular flange 30 which projects outwardly beyond said casing wall, to a cylindrical skirt 31 which is positioned in 110 115 120 125 130

spaced parallel relation to the wall of the casing 5'. The free circumferential edge of the skirt wall is formed with an annular bead 32 which is closely held by the inherent resiliency of the metal in contact against the peripheral surface of the casing wall whereby the openings 13' in said wall communicate with the sound receiving chamber 33 which is thus formed between the casing

10 wall and the wall of the skirt 31 of the closure head. The flange 30 of this head is provided with spaced apertures 34 through which the articulated sound is finally emitted.

15 From the above, the manner of operation of this form of the device will be readily understood. Thus, when the member 14' is in the position seen in Figure 6 and the device is then inverted, said member moves by 20 gravity into the opposite end of the casing and during such movement expels the air from the chamber 20', causing the same to be forced under pressure through the opening 25' past the element 11' whereby sound is

25 produced. In the initial operation of the gravity movement of the member 14', the sound passes from the chamber 27 through openings 19 between the wall of said member and the wall of the casing 5' in relatively 30 small volume, and hence through the openings 13', the chamber 33 and emission apertures 34 and simulates the spoken pronunciation of the letter "m." When the first of the openings 19 registers with the openings 35 13', the sound is emitted in larger volume and simulates the spoken pronunciation of the letter "a," while as the solid portion of the wall of the member 14' between the spaced openings 19' passes the openings 13' the letter "m" is again sounded and when the other 40 relatively longer openings 19' register with the openings 13' there will be the prolonged sounding of the final vowel letter "a" until the member 14' comes to a final position of rest as shown in Figure 5 of the drawing.

45 It will be appreciated that this alternative construction which consists of very few simply formed elements can be manufactured very cheaply.

50 In the present illustrated embodiments of the invention, I have disclosed an arrangement and correlation of the several parts which it is believed will produce the most satisfactory results in practice. It will 55 be seen that the several individual elements are of simple and substantial construction, and the manner of their assemblage and arrangement within the outer drum or casing provides a device of this character having great durability so that it will withstand severe shocks and jars without serious damage or injury to the several operating parts which would impair their proper functional operation. However, it is possible 60 that the essential features of my present

disclosure might also be incorporated in other alternative constructions and it is accordingly to be understood that I reserve the privilege of adopting all such legitimate changes in the form, construction and relative arrangement of the several parts as may be fairly embodied within the spirit and scope of the invention as claimed.

I claim:

1. In a sound producing device, an air receiving chamber, a tubular air expelling member operating in said chamber, sound producing means through which air is forced in the movement of said member in one direction, a sound receiving chamber 75 having a wall adapted to telescope within said tubular air expelling member in the movement of the latter in the opposite direction, the walls of said air chamber and expelling member being provided with 80 openings therein controlling the emission of sound into said sound receiving chamber in the air expelling movement of said member.

2. In a sound producing device, an air receiving chamber, a tubular air expelling member operating in said chamber, a sound receiving chamber nested within one end of the air receiving chamber and having its 85 wall spaced concentrically from the wall of the latter chamber and adapted to telescope within said tubular air expelling member in the movement of the latter in one direction, sound producing means through which the air is expelled in the movement of said member in the other direction, and the wall of said air expelling member and the wall of said air chamber having coacting means 90 controlling the emission of sound into the sound receiving chamber in the air expelling movement of said member.

3. In a sound producing device, an outer casing, a shell positioned within said casing and fixed to one end thereof, the latter end of said shell being open, a sound producing 95 reed mounted on the other end of said shell, an air expelling member mounted within said shell for gravity movement to expel air therefrom through the sound producing reed in its movement in one direction, and said air expelling member and the wall of said shell having coacting means controlling the emission of sound from the space between the outer casing and said shell 100 through the open end of the shell.

4. In a sound producing device, an outer casing, an air receiving chamber enclosed within said casing having a wall spaced from the casing wall, an air expelling member 105 slidably within said chamber and constrained by the wall thereof against displacement out of coinciding axial relation with said chamber, sound producing means through which air is expelled in the movement of said member in one direction into 110

the space between the wall of said chamber and the outer casing, and said chamber wall and the air expelling member having co-acting means controlling the emission of 5 sound from said space in the air expelling movement of said member.

5. In a sound producing device, an outer casing, a shell enclosed within said casing in spaced concentric relation to the wall there- 10 of and having a rim on one end frictionally engaged over one end edge of the casing wall, a sound producing reed mounted upon the other end of said shell, an air expelling member axially movable within the shell 15 to force the air therefrom in its movement in one direction through the reed into the space between said shell and the casing wall, and said member and the wall of said shell having coacting sound emission controlling 20 means operative in the air expelling movement of said member to vary the character of the emitted sound.

6. In a sound producing device, an outer casing, an air receiving chamber within said 25 casing and concentrically spaced from the wall thereof, the wall of said chamber being provided at one end with means for frictional clamping engagement over the end of the casing wall, a sound receiving cham- 30 ber having a wall positioned within the latter end of the air receiving chamber and provided with means on one of its ends to frictionally engage in the wall of the latter chamber, a sound producing reed, a tubular 35 air expelling member axially movable in said air receiving chamber to expel air therefrom in its movement in one direction through the sound producing reed, said tubular member in its movement in the opposite direction 40 telescopically receiving the wall of said sound receiving chamber, said latter wall and the wall of said tubular member having openings therein controlling the emission of sound in the air expelling movement of said 45 member into said sound receiving chamber.

7. In a sound producing device, an outer casing having an air receiving chamber therein, a gravity movable air expelling member mounted in said chamber, said mem- 50 ber being of tubular form, sound produc- 55 ing means through which the air is ex- pelled, a wall enclosed within one end of said chamber and providing a sound receiving chamber, said wall having openings therein, and said tubular member provided with means coacting with means on the wall of 60 said air chamber to control the emission of sound into said sound receiving chamber

during its air expelling movement and said member telescopically receiving the wall of 60 said sound receiving chamber in its move- 65 ment in the opposite direction.

8. In a casing having a sound producing device, an air receiving chamber therein and emission openings in the casing wall, an air 70 expelling member mounted for reciprocating movement within said casing, sound produc- 75 ing means through which the air is expelled from said chamber in the movement of said member in one direction, and said member being provided with means to coact with the emission openings in the wall of said cas- 80 ing during such air expelling movement of said member and effect the articulated emis- 85 sion of the sound through the latter open- 90 ings.

9. In a sound producing device, a casing open at one end and having an air receiving chamber therein, an air expelling member having reciprocating gravity movement in 80 said casing, a fixed sound directing wall within said casing in spaced relation to the open end thereof, sound producing means through which the air is expelled from said chamber in the movement of said member in one direction, and said member and the wall of said casing having coacting means 85 operative in the movement of said member in one direction to control the emission of sound into the space between said fixed wall and 90 the open end of the casing.

10. In a sound producing device, a cas- 95 ing open at one end and having an air re- 100 ceiving chamber therein, a tubular air ex- 105 pelling member mounted in said casing for gravity reciprocating movement, sound pro- 110 ducing means through which the air is ex- pelled from said chamber, a fixed sound di- 115 recting wall arranged within the casing in spaced relation to its open end and disposed in a plane at right angles to the direction of movement of said expelling member, said wall being received within the tubular ex- 120 pelling member in the movement of the latter in one direction and said tubular mem- 125 ber and the casing wall having coacting means operative in the movement of said expelling member in the opposite direction to control the emission of sound into the space between said fixed wall and the open 130 end of the casing.

In testimony that I claim the foregoing as my invention, I have signed my name hereunder.

LEO J. GRUBMAN.
